UNITED STATES PATENT OFFICE.

FRANK K. RUSSELL, OF DALLAS, TEXAS.

LEATHER-WORKING MACHINE.

1,268,158.

Specification of Letters Patent.

Patented June 4, 1918.

Application filed August 15, 1911. Serial No. 644,223.

To all whom it may concern:

Be it known that I, FRANK K. RUSSELL, a citizen of the United States, residing at Dallas, in the county of Dallas and State of 5 Texas, have invented certain new and useful Improvements in Leather-Working Machines, of which the following is a specification.

This invention relates to leather-working machines and particularly to machines for finishing straps, traces and similar articles, and the object is to construct a machine which will, with one passage of the strap through the machine, perform the various 10 operations set forth. After a strap has been cut out of a side of leather, it is subjected to various treatments, and heretofore without my machine straps have been finished only after passing through a number of operations performed by hand by one or more persons who use one or more machines. The edges of some kinds of straps must be trimmed and then blacked or stained. The 15 strap then goes through various smoothing processes and must usually be properly creased by means of suitable rollers or creasing devices. The edges of the strap must be still further rubbed so that the fiber will be made compact and smooth. The machine is 20 further provided with rubbing devices which will approximate the act of rubbing a strap by hand. All of the above mentioned operations are provided for in a single machine and most of the devices for same are 25 arranged in pairs and all of the devices are automatically adjustable vertically where necessary, and most of the devices may be laterally adjusted simultaneously. The machine is further provided with feeding devices 30 for starting straps in the machine and drawing the straps through or between the various treating devices. Other objects and advantages will be fully explained in the following description, and the invention 35 will be more particularly pointed out in the claims.

Reference is had to the accompanying drawings, which form a part of this application and specification.

50 Figure 1 is a side elevation of the machine showing the parts as complete as is practicable on one sheet of drawing. Fig. 2 is a plan view of the same. Fig. 3 is a front end elevation of the same upon an enlarged 55 scale. Fig. 4 is an enlarged plan view of one side of the trimming devices. Fig. 4^a is a side elevation of a scrap pan. Fig. 5 is an enlarged detailed view of the handle for raising the vertically adjustable frame of the trimming devices. Fig. 6 is a plan view 60 of the stripper for detaching the work from the feeder. Fig. 7 is an enlarged detailed view of one of the feeders. Fig. 8 is a cross section of the devices for holding the feeder. Fig. 9 is a longitudinal section of the feeder-holding devices. Fig. 10 is a plan view of the same. Fig. 11 is a side elevation of the devices for pressing the work on the feeder. Fig. 12 is a broken plan view of the starting devices. Fig. 13 is a detailed view of a 65 hanger which carries a roller for holding the teeth of the feeder out of contact with the pressing-on springs. Fig. 14 is a vertical section of the cleaning brushes located at the rear end of the machine for the final rubbing 70 of the straps. Fig. 15 is a detailed view showing the manner of placing the lower brushes for the same. Fig. 16 is a plan view of the right side of one of the edge-blackening devices. Fig. 17 is a broken sectional view 75 of the same. Fig. 18 is a side elevation of the trough containing the blacking, showing the location of the blacking-applying brush. Fig. 19 is a plan view, partly in section, of one of the blacking devices, this device being 80 for blacking the flesh side of the strap. Fig. 20 is a cross section taken along the line $x-x$ of Fig. 19. Fig. 21 is a front elevation of the device shown in Fig. 19. Fig. 22 is a 85 side elevation of the device shown in Fig. 21, looking at the left side of Fig. 21. Fig. 23 is a front elevation of the right edge burnishing devices and showing a side elevation of the pressing weights. Fig. 24 is a side elevation of the same. Fig. 25 is a broken 90 vertical section of the vertically adjustable edge burnishers. Fig. 26 is a plan view of the top and bottom smoothing devices. Fig. 27 is a front elevation of the same. Fig. 28 is a vertical section, taken along the line 95 $y-y$ of Fig. 27. Fig. 29 is a side elevation of a rubbing device. Fig. 30 is a front elevation of the same in combination with a rubbing device. Fig. 31 is a plan view of the same in combination with a rubbing device. Fig. 32 is a front elevation of the 100 rubber. Fig. 33 is a rear elevation of the guide to the rubber. Fig. 34 is an enlarged detailed view of the guide roller. Fig. 35 is a plan view of the right creasing devices. Fig. 36 is a side elevation of the same. Fig. 110 37 is a front elevation of the same. Fig. 38 is a detail view of the feeder carrier bar.

Similar characters of reference are used to indicate the same parts throughout the several views.

- The present invention consists of certain improvements on my patent for leather-working machines, dated May 18, 1909, No. 922,195. Referring to Figs. 1 and 2 of the drawings, A indicates the devices for receiving and fixing the straps on the feeders. B indicates the trimming devices. C indicates the edge-blacking devices. D indicates the bottom-blacking devices. E indicates the smoothing devices. F indicates devices for brushing the edges of the straps. G indicates creasing devices. H indicates guides. J indicates edge-burnishing devices. K indicates bottom and top smoothing devices. M indicates edge-rubbing devices. N indicates the cleaning brushes at the rear end of the machine. The machine is provided with a frame 1 which is provided with legs 2 at each end. The frame 1 is in two parts rigidly connected together. On the frame 1 is mounted a frame composed of laterally movable portions 3 and 4. The parts 3 and 4 are suspended on shafts 5 and 6, and the shafts 5 and 6 are provided with bearings 7 mounted on the frame 1. The parts 3 and 4 are provided with screw-threaded bearings 8, which engage the shafts 5 and 6. Sprocket wheels 9 are mounted on the shafts 5 and 6 and a sprocket chain 10 is mounted on sprocket wheels 9. The shaft 5 is provided with a crank 11. By means of the crank 11, the frame pieces 3 and 4 may be adjusted closer together or farther apart, as may be desired. The edge operating elements for operating on the edges of straps, are arranged in pairs on the laterally adjustable frame pieces 3 and 4, so that these elements are adapted to operate on straps of any ordinary width.
- The trimming devices B are fully shown and described in the patent above referred to and will not be shown and described in detail in the present application. I have provided an improved scrap-pan for catching the scraps cut from the leather so that these scraps will not interfere with the working of the machine. A pan 12 is mounted on each side of the frame 1. The feeders pass between these two pans, which have upwardly projecting flanges 13, Fig. 4. To each flange 13 is pivoted an arm 14 and this arm is movable vertically at one end, which end is supported by a spring 15. The arms hold the shavings of leather above the path of the feeders so that the hooked teeth of the feeders will not drag the scraps or shavings into the machine. But the arms being yieldingly supported by means of springs 15, when a strap is being carried past the trimmer by a feeder the straps will ride over the arms, pressing the same out of the path of the strap. In Fig. 5 the guide

rod 16 is shown provided with a handle 17 for convenience in raising the vertically adjustable frame which carries the trimming blades for the upper side of the strap, and by reason of the cam on the handle the frame may be held elevated while blades are being changed or adjusted.

The mechanism for receiving and starting a strap in the machine is shown in Figs. 11 and 12, which are detailed views on a larger scale than Figs. 1 and 2. The receiving and starting mechanism is mounted on bars 18 which are attached to the main frame or stationary frame. A bracket 19 is mounted on the bars 18. Springs 20 and 21 are bolted to the bracket 19 and curved under the bracket, as shown in Fig. 11. The spring 21 is extended forward of the bracket 19. Three springs 22, 23, and 24 are attached to the spring 21 and a rod 25 connects the forward end of the spring 21 with the two springs 20 and 21, as shown in Fig. 11. The ends of these springs constitute bars for pressing the straps on the feeders and are held just above the teeth of the feeders by the rod 25 which is adjustable by the nut 26. These bars have upward yielding motion to permit the passage of straps of different thicknesses. A starting spring 27 is bolted to spring 20 to press a strap slightly on the teeth of a feeder when the strap is starting in the machine. The straps are secured firmly on the teeth of the feeder by means of the springs 20 and 21. If it were not for the springs 22, 23 and 24 the strap might tilt upward just as the feeder passes from under the springs 20 and 21, and thus become loose on the feeder. The springs 22, 23 and 24 become weaker in progression up to the spring 24 so that the pressure on the strap is relieved gradually. The bracket 19 is braced on each side by rods 29 which are bolted to the stationary frame and to the sides of the bracket by suitable nuts and flanges 30. The machine is provided with a guard 31 which is attached to the lower part of the frame and extends in a curve upward and above the outer ends of the bars 18, as shown in Figs. 11 and 12, and is attached to the bars 18 by suitable bolts 32. The guard 31 is bifurcated at the upper end for the passage of the feeder 28. 33 and 34 indicate straps of different thicknesses which may be treated by the machine, and the drawing shows the points at which the straps are to be fed to the machine. A movable clip or shield 35 is mounted on the guard 31 above the bend in the guard and stands normally in the position shown in Fig. 11 and is held in this position by spiral spring 36, which may be attached to the lower part of the guard 31 and to the shield 35. A dog 37 is pivoted to the shield 35. The feeder 28 engages the dog 37 by means of the shoulder 38, and the dog 37 moves in 130

a slot in guard 31 and carries the shield 35 therewith until the dog swings back on the left hand side of the guard 31 by reason of the notch 40 in the side of the dog 37 and remains there until the feeder passes. When the dog 37 is released by the feeder 28 the spiral spring 36 draws the shield 35 back to its normal position. The shield 35 goes through this operation as often as the feeder 28 passes through the shield. When the shield is carried to the strap which is ready for starting by the feeder the shield covers all the teeth of the feeder except the forward teeth. Consequently the extreme forward end of the strap must engage the forward teeth of the feeder and in this manner all the teeth of the feeder are made to engage the strap and it is impossible for the strap to be engaged by the rearward teeth only of the feeder for the reason that the rearward teeth are covered by the shield. If the front teeth of the feeder engage the strap then the springs 20 and 21 will press the strap on all the teeth of the feeder. The guide arms 41, Fig. 3, are attached to the adjustable frame of the machine and serve to center the strap on the feeder. By means of these arms, together with the spring 27 the strap may be properly started into the machine and the straps are afterward properly fixed on the feeder. The feeders 28 are carried by two sprocket chains 42 and 43. Depressible guides 42' are provided for the chains 42 and 43. These guides 42' are mounted by means of brackets 42'' on the frame 1 by bolts or rods 43' on which are mounted coil springs 43''. Washers 44' form spring seats for springs 43''. The guides 42' have a fixed upper limit in brackets 42'', but are provided with yielding supports in springs 43'' so that the guides can be depressed automatically to allow a passing strap to adjust itself in the finishing devices. These sprocket chains 42 and 43 are endless and connected together at intervals and carry at intervals a plate 28 which constitutes a feeder. The sprocket chains 42 and 43 are connected together by bars 44. The feeders or plates 28 are mounted on the bars 44 by the following devices: The bars 44 carry downwardly projecting lugs 45. Connections 45' and 45'' are pivotally attached to the lugs 45. A bar 46 is pivotally mounted in the connections 45' and 45''. The bar 46 has cylindrical portions 47 and a coiled spring 48 is mounted on one end of the bar or holder 46 and presses against the connection 45'' and against a shoulder 46' on the bar 46. The bar 46 is prevented from turning by lugs 47' which project into a groove in the connection 45'. The compression spring 48 holds lugs 47' normally in the groove, but will yield sufficiently to permit the turning of the bar 46 so that the feeder 28 can be turned out of the path of the straps. The bar 46 has pintles or journals 47'' which turn freely in the connections 45' and 45'' and have free axial movement therethrough and also through the bars 44. The bar 46 carries tapering or conical pins or lugs 46'' which together with a spring clamp 48' hold the feeder 28 normally in operative position, but by reason of the taper of the pins 46'' and the spring 48' the feeder will slide off the pins 46'' if the feeder should come against some rigid object or be subject to abnormal strain against forward movement and thus not be broken. The feeder holder is rotatively and slidingly connected to the carrier chain. The lugs 47' serve to hold the feeder 28 in an upright position, but the spring 48 is yielding so that the feeder 28 can be turned down laterally out of the way of straps which are being operated upon in case the strap is longer than the space between two feeders. The feeders 28 are supposed to be mounted on the double sprocket chain at suitable distances so that a feeder will not interfere with the strap which is being carried by the feeder in advance, but as above explained, in case of a very long strap some of the feeders can be turned down out of the path of the straps. The feeder 28 is attached to the bar 46 by lugs 46'' and by the spring clamp 48'. The sprocket chains are driven by the wheels 50, one being located at each end of the machine on shafts 51 which are provided with bearings 52'. The path of the feeder is so close to bar 20 that there is danger of the feeder teeth striking the bar 20 and mutilating the bar or injuring the teeth of the feeder. To prevent such accident a hanger 52 is bolted to springs or bars 20 and 21. This hanger carries a roller 53. The bar 46 which carries the feeder will pass under the roller 53 and while the bar 46 is passing under the roller 53 the teeth of the feeder can not strike the spring 20 because the distance between the bottom of the spring 20 and the bottom of the roller 53 is permanently fixed and greater than the distance between the top of the bar and the top of the teeth. The feeders consist of plates of metal. Each feeder is provided with a plurality of teeth 54 and the forward edge of the feeder is provided with a shoulder 55 to prevent the strap from being pressed farther down on the front tooth than on the other teeth. But for the shoulder 55 the fixing spring would press the strap down too far on the front tooth because the spring strikes the front tooth with a more direct thrust than it strikes the other teeth. The teeth are more slanting at the forward edge than at the rear edge, and each tooth 54 from front to back approaches or tends to approach a more upright position as shown

in Fig. 7, so that each tooth will stand at the proper angle to enter the strap approximately in line with the motion of the strap with reference to the tooth at the time of the entering. It will be seen that the strap will assume different angles from the time of the engagement of the front tooth and the time of engaging the last tooth, as indicated by dotted lines A B and A C. Each tooth has a barb 56 on the under side to prevent a premature releasing of straps.

The first operation on straps which the machine is adapted to perform is trimming, above noted.

15 The next operation after the straps have been trimmed is the blacking of the edges of the strap. For this purpose rotary brushes 57 are mounted in troughs 58 and the troughs 58 are integral with frame pieces 59, which are bolted to the movable frame pieces 3 and 4. The straps pass over the inner edges of the troughs 58 and the edges of the troughs form seats for the straps. The rotary brushes are mounted on 20 shafts 60. Each shaft 60 is driven by a pulley 61 and belt 62 and the belt is driven by a pulley 63 which is mounted on the shaft 51. Each shaft 60 is provided with an adjustable collar 64 against which presses 25 a spiral spring 65. These springs keep the brushes pressed toward the edges of the strap. In this manner the wear of the brushes is taken up. The springs 66 and the beveled approach 79" to the troughs 30 35 guide the straps to the brushes. The troughs 58 are supplied with blacking from cans 67. Each can 67 is provided with a mouth or spout 68 which is inverted with the spout 68 in the trough. The blacking will run out 40 until sufficient blacking is in the trough to prevent the atmosphere from entering the spout. As the blacking is used up by the brush 57 more blacking will run out of the can, but the flow will stop as soon as the 45 blacking closes the mouth of the spout 68.

After the edges of the strap have been blacked the lower or flesh side of the strap is blacked. For this purpose the troughs 69 are attached to the frame 1. The rotary brushes 70 are mounted in the troughs 69 on shafts 71. The shafts 71 are driven by pulleys 72 and belts 73 and pulleys 74 which are mounted on shafts 60. The troughs 69 are supplied with blacking from cans 75 50 which operate in the same manner as the cans 67 above described, cans 75 being provided with spouts 76. The troughs 69 have shallow portions 77 in which are located 55 standing brushes 78 for brushing that part of the bottom of the straps which has not been blacked by brushes 70 as the straps pass over the troughs. The bristles of brush 78 will be forced apart in the center by the feeder and the bristles are so arranged that 60 they by their resiliency close the opening 65

made by the feeder after the passage of the feeder. The shafts 71 are maintained in adjusted position by springs 70'. As the straps are passing over the brushes 70 and 78 they are held down by weights 79. The weights 70 79 are held in place by upwardly projecting posts 80. The feeders 28 force the straps under the weight 79 by reason of the V-shaped approach 79'.

After the straps have been blacked they 75 pass through smoothing devices shown in detail in Figs. 26, 27 and 28. A bracket 81 is attached to each of the frame pieces 1 by means of outwardly projecting flanges 82. The brackets 81 have inwardly projecting 80 ledges 83 and bearings 84. Guide rods 85 are mounted in the bearings 84 and ledges 83. A plate 86 has bearings 87 on each side thereof which receive the guide rods 85 and rest on the ledges 83. The bearings 87 are 85 held yielding downward on the ledges by spiral springs 88. The plate 86 is set at an angle so that straps of any ordinary thickness will be received between the plate 86 and the ledges 83. The spiral springs 88 90 will cause the plate 86 to press yielding on the straps as they are passing through the smoothing devices. Wipers 89 are attached to the plate 86, and to ledges 83 by means of the brackets 90. A hanger 91 is 95 attached to plate 86 for carrying a roller 92. The roller 92 rides on the bars 46 of the double sprocket chain and causes the plate 86 to rise high enough or causes the bar to sink low enough to prevent the teeth of the 100 feeder from striking the plate 86. This will prevent the feeder from mutilating the plate and prevent the plate from injuring the teeth of the feeder.

After the strap leaves the smoothing devices the edges of the strap are brushed by fast-rotating brushes 127 which are mounted on shafts which are journaled in vertical bearings 128 and driven by pulleys 129 and belts 121. These brushes run with sufficient 110 speed to remove the surplus blacking which is thrown to the guards 127' by centrifugal force, from which it drops into drip pan 127" and drains into a receptacle 128.

The creasing devices are shown in Figs. 35, 115 36 and 37. The creasing devices are arranged in pairs. Only one of the pairs will be described. A frame piece 93 is attached to the laterally movable frame piece 4. This frame piece 93 carries a ledge 94 on which the 120 straps are received and guided to the creasing rollers 95 and 96. The creasing roller 95 is mounted on a shaft 97 which is journaled in a bearing 98 carried by the frame 93. The upper creasing roller 96 is mounted on a 125 shaft 99 which is journaled in a bearing 100 which bearing is mounted on stud 100' and is held down by a yielding frame piece 101 which is pivotally mounted on a stud 102, which stud 102 is rigid with the frame 130

93. The stud 100' is also rigid with frame 93. The frame 101 has an upwardly projecting bar 103 and a spring bar 104 rests on the bar 103 at one end and at the other 5 end on the frame 93. A screw 105 is threaded and screws through a bearing 106 which is rigid with the frame 93. This screw 105 terminates with a crank by which it may be screwed down more or less on the 10 bar 104 to increase or decrease the pressure of the creasing roll 96 on the strap which is passing between the rolls 95 and 96. The frame piece 101 carries a guide plate rigid therewith. This guide plate 107 receives the 15 straps and is set at an angle to receive a strap of any ordinary thickness. Means are provided for driving the creasing rollers 95 and 96. The sprocket chain 42 drives a sprocket wheel 108. This sprocket wheel 20 drives a shaft 108'. Shaft 108' drives a cog wheel 109. Cog wheel 109 drives an idler cog wheel 110. Cog wheel 110 drives a cog wheel 111 which drives shaft 97 and cog wheel 112 and roll 95. Cog wheel 112 drives 25 idler cog wheel 113 which drives an idler cog wheel 114. This cog wheel 114 drives a cog wheel 115 which drives shaft 99 and roll 96. A spring actuated catch 130 is provided for holding the wheel 96 in place and 30 may be raised for removing and replacing said creasing roll. The roll 96 is vertically adjustable and may be driven in the different vertical adjustments by reason of the fact that the gearing 114 and 115 is maintained 35 at the same distance apart by the bearing 100 and the arms 100' which are integral with bearing 100 and which are pivoted on stud 100'. The bearing 100 thus has an upward swinging motion and cog wheel 115 40 will engage cog wheel 114 at different vertical adjustments.

The cog 111 is keyed to shaft 97 and is movable axially on said shaft by reason of the key way 97' whereby the creasing rolls 45 may be driven at any desired lateral adjustment, the creasing rolls being moved laterally by the bracket 93 which is carried by the frame piece 4.

After the edges of the strap have been 50 creased, the edges of the straps are burnished to make the same smooth and compact by the devices shown in Figs. 23 to 25 inclusive. An upright driven shaft 116 is mounted in a bearing 122 which is mounted on a pivot 55 shaft 122' which is mounted in a bracket 117 which is attached to the movable frame piece 4. The bearing 122 is held normally against the wedge 131' by a spring 122''. The shaft 116 is provided with a pulley 118 which is 60 engaged by a belt 119. A pulley 120 which is integral with pulley 118 is engaged by a belt 121. A plurality of burnishing rings 123 are mounted on the shaft 116. These 65 disks or rings have projections or teeth 124 which partly intermesh, that is, the teeth of

one disk mesh with the teeth of the adjacent disk. The bottom disk is rigidly mounted on shaft 116 and the other disks are loosely mounted on the shaft 116 so that the disks are vertically movable. This provision is to 70 make the grooves formed between the disks conform to the thickness of any ordinary strap. The disks 123 are held yieldingly down by a spiral spring 125 which is held down by a pin 126. The teeth 124 are beveled from the inside and terminate with approximately sharp edges, so that there will be a minimum amount of surface between the edges of the teeth and the adjacent disk. The object of this construction is to prevent 80 particles of leather or ink from accumulating in a position to hold the disks 123 apart. The disks 123 have upwardly extending hubs which perform two functions. The hub will form a bearing to hold the disks in a proper horizontal plane and prevents dirt from accumulating on shaft 116.

Provision is made for holding the burnishers 123 at different vertical adjustments. The pulleys 118 and 120 may be formed integral. The pulley 120 rests against the top of bearing 122. The hub of pulley 118 has a notch therein and a plurality of holes are made in the shaft 116. A pin 118' is to be inserted in the holes to hold the shaft at 95 different heights. The pin rests in the notch in the hub. The distances between the holes in shaft 116 correspond to the difference between the grooves formed by the disks 123. A strap may be made to enter any one of the 100 grooves by setting the pin in the hole in shaft 116 which will raise the groove to the desired height.

The bracket 117 and bearing 100 carry devices for regulating the pressure of burnishers 123 on the straps. An arm 131 is attached to bearing 100 and projects between bearing 122 and cam 132. The object of this arm 131 is to regulate the pressure on the burnishers 123, in proportion to the thickness of the straps. As the roll 96 is raised upward by a passing strap, the arm 131 forces the wedge shaped member 131' between the bearing 122 and the cam 132, 115 thereby forcing the teeth 124 of the disk 123 against the straps. A lever 133 is rigid with the pivot shaft 135 of the cam 132. A rack may be formed integral with the bracket 117 for holding the lever 133 in different positions to cause a thicker or thinner part of the cam 132 to come against the wedge member 131' which operation furnishes additional means of regulating the pressure of the burnishers. The shaft 135 of the cam is axially yielding and a spring 136 is attached 120 to the bracket 117 and presses against the end of the shaft 135 and thus holds the lever 133 on rack 134. A bolt 136' presses against the cam 132 to hold the cam in position 125 against the wedge 131'. 130

Guides H direct the straps to the burnishers 123 so that the edges of the strap will enter the grooves of two pairs of disks which are opposite to each other in the same horizontal plane. These guides are shown in other places on the machine in front of different operating elements. The guides are shown in detail in Figs. 29 to 34 inclusive in connection with the rubbing device. A carrying bracket 137 is bolted to the frame piece 4. This bracket has bearings 138 for a shaft 139 on which is mounted a spring 140, one arm of which rests against the bracket 137 and the other arm of which rests against a yoke 141 and holds this yoke yieldingly down. A roller 142, is journaled in a bearing 143 which is formed integral with the yoke 141 and the yoke 141 is pivotally mounted on the shaft 139. The roller 142 is thus yieldable upward. A ledge 144 is formed on the bracket 137. The strap is received on the ledge 144 and under the roller 142 and the roller will yield to allow a strap of any thickness to pass thereunder. In Figs. 29 to 32 inclusive a rubbing device is shown in rear of the guiding devices. The rubber 145 is attached to the frame 4 by a supporting bracket 146 and is provided with a groove 147 to receive the edge of a strap. The rubbers may be placed at several locations, as shown in Figs. 1 and 2.

Adjacent to the rubbers M is mounted a driving shaft 148. Power may be applied to this shaft by a pulley 149 which may be driven by any suitable power. Pulleys 150 are mounted on this shaft 148 for driving the belts 119 which drive the edge burnishers.

After the straps leave the rubbers M they are cleaned by brushes. A casing 151, Fig. 14, in two parts, right and left, is mounted on the frame 1 on each side thereof. An upper casing is pivotally mounted above the two casings 151 on a pivot shaft 163'. A horizontal slot 152 is left between the upper casing 161 and the two lower casings 151 for the passage of straps and the two casings 151 are located far enough apart to leave a vertical slot for the passage of the feeder. A pair of right and left brushes 153 are journaled in the two casings 151 and set at an angle. The bristles which form the brushes are arranged in cone shapes, the large ends projecting in close proximity to the path of the feeder and the two rotary brushes are set at an angle so that the two brushes will present a continuous surface on the top side thereof. Thus the strap is brushed entirely across the top and entirely across the bottom. The object of having two shafts or two brushes is to permit the passage of the feeders and the object of the cone-shaped brushes set at an angle is that the bristles may close the passage of the feeders and brush all parts of the lower side

of the strap. The shafts 154 are driven by pulleys 155 and belts 156, the latter being driven by pulleys 157 which are mounted on shaft 148. A brush 158 is mounted in the upper casing 161 and is driven from the same shaft 148. The casing 161 is provided with a dirt box 159 for gathering the dirt or other matter thrown from the straps by the brushes. The upper part 161 is yielding and is held in operative position by the spiral spring 162 which is attached to the outside of the casing and to bracket 163 which is rigid with the frame 1. The spring 162 partly supports the casing 161 and prevents the casing from resting too heavily on passing straps. The greater part of the dirt will pass between guards 160' and 167 and fall out, and practically all the dirt which remains momentarily in the bristles will be thrown through slot 161' into box 159.

A guard 164 is attached to the rear of the machine to prevent workmen from coming in contact with the feeders. After the straps pass under the rear end of the machine and as they approach the front end of the machine, they are stripped from the feeders by the stripper 165. The stripper has a slot 166 to receive the feeders and the stripper is curved downward and backward so that the teeth of the feeders will pass through the slot and leave the strap to fall.

Having fully described my invention, what I claim as new and desire to secure by Letters Patent, is,—

1. In a leather strap finishing machine, edge trimming devices, feeders for drawing straps through the trimming devices; a pair of scrap pans arranged on opposite sides of and adjacent to the passage of said feeders and a yieldingly mounted bar connected to each pan holding the scraps above the feeders.

2. A leather strap finishing machine having a pair of edge blacking devices comprising a trough on each side of the passage of the strap, a rotary shaft projected into each trough, a rotary brush mounted on each shaft, means for driving said brushes, and a tank for supplying blacking to each trough having a spout projecting from the tank down into the trough and having a portion of one side of the spout cut away.

3. In a leather strap finishing machine, a pair of edge blacking devices comprising a trough on each side of the passage of straps, a rotary brush mounted in each trough, a spring mounted on each trough for guiding straps thereto; and an inverted tank having a spout projecting down into each trough.

4. In a leather-working machine, a pair of edge blacking devices comprising a trough on each side of the passage of straps, a rotary brush mounted in each trough, a spring mounted on the shaft of each brush, said

springs serving to force the shafts axially toward each other for keeping the brushes constantly in contact with the edges of passing straps, and means for varying the tension of said springs.

5. In a leather strap finishing machine, bottom blacking devices comprising a pair of troughs, each trough having a deep portion and a shallow portion, rotary brushes mounted in the deep portions of said troughs, stationary brushes mounted in the shallow portions of said troughs and co-operating with said rotary brushes, and means for supplying said troughs with 10 blacking.

6. In a leather strap finishing machine, devices for blacking the bottom of straps comprising a pair of troughs, each trough having a deep portion and a shallow portion, 20 a rotary brush mounted in the deep portion of each trough, a stationary brush mounted in the shallow portion of each trough, vertically movable weights for holding straps down on the brushes mounted on said troughs and means for supplying blacking to said troughs.

7. In a leather strap finishing machine, devices for feeding straps, devices for blacking the bottom of straps comprising a pair 30 of troughs, each trough having a deep portion and a shallow portion, a rotary brush mounted in the deep portion of each trough, and stationary brushes mounted in the shallow portions of the troughs and 35 serving to close the passage of the feeding devices after the passage of the feeding devices.

8. In a leather strap finishing machine, creasing rolls, means yielding vertically and 40 actuated automatically by passing straps to permit the opening of said rolls proportionately to the thickness of approaching straps, and gearing for driving said rolls at different vertical adjustments.

45 9. In a leather strap finishing machine, creasing rolls, means yielding vertically and actuated automatically by passing straps to permit the opening of said rolls proportionately to the thickness of approaching 50 straps, and gearing for driving said rolls in different positions in which said rolls may be located, said creasing rolls being laterally adjustable and said gearing being provided with shafts by which said gearing 55 may be laterally adjusted with said creasing rolls.

10. In a leather strap finishing machine, edge burnishing devices comprising oppositely disposed vertical shafts and pairs of 60 vertically yielding disks having intermeshing pressing surfaces forming grooves to receive the edges of straps and having upwardly projecting sleeves about said shafts.

11. In a leather strap finishing machine, 65 edge burnishing devices comprising pairs of

vertically yielding disks provided with curved intermeshing members for forming expansible grooves, vertical shafts for said disks, and brackets carrying laterally swinging bearings for said shafts.

70

12. In a leather strap finishing machine, edge burnishing devices comprising pairs of vertically yielding disks forming grooves to receive edges of straps, oppositely disposed vertical shafts for said disks, brackets 75 carrying swinging bearings for said shafts, cams and wedges for adjusting said brackets, and springs tending to press said shafts away from each other.

13. In a leather strap finishing machine, 80 edge burnishing devices comprising pairs of vertically yielding disks oppositely disposed and forming grooves to receive edges of straps, laterally yielding bearings, vertical shafts journaled in said bearings, driving 85 pulleys mounted on shafts above said bearings, and pins inserted in said shafts and resting in notches in the hubs of said pulleys, said shafts having holes at different vertical adjustments for said pins whereby 90 said shafts may be supported at different vertical adjustments.

14. In a leather strap finishing machine, edge burnishing devices comprising pairs of 95 disks having curved intermeshing members for forming expansible grooves, vertical shafts driving said disks, swinging bearings for said shafts and means for pressing said bearings toward each other.

15. In a leather strap finishing machine, 100 edge burnishing devices comprising pairs of disks forming grooves for the edges of straps, vertical shafts for driving said disks, brackets, bearings for said shafts having arms pivotally connected with said brackets 105 whereby said bearings have swinging motion toward and from each other, and wedging members operating between said brackets and said bearings for pressing said bearings toward each other.

110 16. In a leather strap finishing machine, the combination of creasing devices and edge burnishing devices, said edge burnishing devices comprising edge burnishers, vertical shafts driving said burnishers, brackets, 115 swinging bearings for said shafts having arms pivotally connected with said brackets whereby said bearings are movable toward and from each other, and wedging members operated by said creasing devices for varying the pressure of said bearings toward each other.

17. In a leather strap finishing machine, the combination of creasing devices and edge 125 burnishing devices, said edge burnishing devices comprising edge burnishers, vertical shafts driving said burnishers, brackets, swinging bearings for said shafts having arms pivotally connected with said brackets whereby said bearings are movable toward 130

- and from each other, wedging members operated by said creasing devices for varying the pressure of said bearings toward each other, and cams mounted on said brackets and coöperating with said wedging members.
18. In a leather strap finishing machine, the combination of creasing devices and edge burnishers, vertical shafts driving said burnishers, brackets, swinging bearings for said shafts having arms pivotally connected with said brackets, whereby said bearings are movable toward and from each other, wedging members operated by said creasing devices for varying the pressure of said bearings toward each other, cams mounted on said brackets, and means for causing said cams to coöperate with said wedging members. 70
19. In a leather strap finishing machine, the combination of creasing devices and edge burnishers, vertical shafts for said burnishers, brackets, swinging bearings for said shafts having arms pivotally connected with said brackets whereby said bearings are movable toward and from each other, wedging members operated by said creasing devices for varying the pressure of said bearings toward each other, cams coöperating with said wedging members, rocker-shafts for said cams journaled in said brackets, levers rigid with said rocker-shafts, and racks for holding said levers at different adjustments. 80
20. In a leather strap finishing machine, the combination of edge rubbing devices provided with grooves and guides for directing straps into the grooves of said edge rubbing devices comprising ledges in line with the lower edges of said grooves and vertically yielding rollers coöperating with said ledges. 90
21. In a leather strap finishing machine, smoothing devices comprising a slotted lower plate, a vertically yielding inclined upper plate, feeders running in the slot of said lower plate, and a guard suspended on said upper plate and spacing the feeders from said upper plate. 95
22. In a leather strap finishing machine, smoothing devices comprising a slotted lower plate, a vertically yielding upper plate, feeders running in the slot of said lower plate for drawing straps between said plates, and a roller and hanger therefor spacing said feeders from said upper plate. 100
23. In a strap-finishing machine, elements operating on passing straps and feeding devices for engaging the straps having a belt carrying at intervals upwardly projecting plates, and each plate having a series of forwardly inclined teeth, each tooth from forward to rear part making a greater angle with the feeder plate than the next forward tooth. 110
24. In a strap-finishing machine, elements operating on passing straps and strap feed- 120
- ing and starting devices comprising means for directing a strap into the machine, a pressing on bar, a belt carrying at intervals upwardly projecting toothed plates, and a guard for preventing the teeth of said feeders from striking said pressing on bar. 125
25. In a strap-finishing machine, elements operating on passing straps and strap feeding and starting devices comprising means for directing a strap into the machine, a pressing on bar, a belt carrying at intervals bars and upwardly projecting toothed plates, and a roller guard and hanger therefor attached to said pressing on bar for spacing said plates from said pressing on bar. 130
26. In a strap-finishing machine, strap feeding devices and devices for operating on straps including cleaning devices comprising a pivotally mounted casing, a rotary brush journaled in said casing, a spring suspending said casing with the bristles of the brush projecting in the path of straps, a casing in two parts mounted beneath said pivoted casing with space between said parts for the passage of feeding devices, and rotary brushes having bristles therein conical in form journaled at angles in said last named casings whereby the bristles thereof will close the passage of the feeding devices after the passing of the feeding devices. 140
27. In a strap-finishing machine, elements operating on passing straps and a strap carrying device having tapering pins, a toothed strap engaging device mounted on said tapering pins, and a yielding pressing member holding said strap engaging device on said pins to permit detachment of said strap engaging device under abnormal strain. 150
28. In a strap-finishing machine, elements operating on passing straps and a carrier, a device for engaging and carrying straps, carried by said carrier, and a yielding member holding said device normally in operative position but permitting detachment from operative position under abnormal strain. 160
29. In a strap-finishing machine, elements operating on passing straps and a carrier operated by said machine and a strap engaging member rotatively and slidingly connected with said carrier. 170
30. In a strap-finishing machine, elements operating on passing straps and a carrier chain having cross bars provided with recesses therein and a strap carrying member having pintles rotatively and slidingly connected with said bars. 180
31. In a strap-finishing machine, elements operating on passing straps and a carrier chain having cross bars provided with recesses therethrough, a strap carrying member provided with pintles rotatively and slidingly connected with said cross bars and a yielding pressing member holding said strap carrying member normally in opera- 190

tive position but permitting displacement thereof under abnormal strain.

32. In a strap-finishing machine, elements operating on passing straps and a carrier chain having cross bars, rocking connections pivotally connected to said bars, one of each pair of said connections having a groove therein a strap carrying member having pintles rotatively and slidably connected with said connections, lugs on one end of said strap carrying member projecting in said groove, and a spring on the other end of said strap carrying member pressing said lugs in said groove.

33. In a strap-finishing machine, elements operating on passing straps and a feeder carrier having tapering lugs projecting therefrom, a strap engaging member mounted on said lugs, and a spring clip holding said member in normal operating position but yielding to allow detachment of said member under abnormal strain.

34. In a strap-finishing machine, elements operating on straps and a strap carrying member provided with teeth, a pressing member for forcing straps on said teeth, and means for forcing said pressing member out of the path of said teeth whereby said pressing member may be held yielding in the path of said teeth and be caused to move just out of the path of said teeth at the time of the passage of said teeth.

35. In a strap-finishing machine, elements operating on straps and a bar and a feeder member carried by said bar and provided with teeth, a pressing member for forcing straps on said teeth, a roller attached to said pressing member and adapted to bear on said bar, whereby said pressing member may be held just out of contact with said feeder teeth.

36. In a strap-finishing machine, devices for applying blacking comprising a receptacle for holding the blacking while being applied and a reservoir for automatically supplying blacking thereto, brushes in said receptacle for applying blacking, and springs for pressing said brushes against passing straps.

37. In a leather-working machine, rotary brushes provided with shafts for applying liquid to passing straps and springs for forcing said shafts axially toward each other for holding said brushes against the said straps.

38. In a leather strap finishing machine, edge blacking devices having seats for straps and pressing fingers and beveled weights for guiding and for holding the straps of various thicknesses on said seats.

39. In a leather-working machine, edge blacking devices consisting of blacking troughs, rotary brushes in said troughs, shafts horizontally disposed and carrying said brushes, springs for forcing said shafts

axially toward each other for holding said brushes in position, and fingers for guiding and holding the straps in contact with said brushes.

40. In a leather strap finishing machine, devices for applying liquid to the sides of straps having troughs, brushes in said troughs, a weight having a beveled approach for guiding and for holding the strap against the brushes and guides preventing displacements of said weight.

41. In a leather strap finishing machine, devices for applying liquid to the sides of straps having troughs, brushes in said troughs, a weight coöoperating with said brushes, said weight having its forward end beveled whereby the strap may raise said weight, and guides for preventing displacements of said weight.

42. In a leather strap-finishing machine, elements operating on passing straps and a chain feeder carrier and guides therefor and yielding supports for said guides whereby said carrier is automatically adjustable to the work being done.

43. In a leather strap-finishing machine, elements operating on passing straps and a chain feeder carrier and guides therefor, brackets fixing an upper limit to the movement of said guides, and yielding supports for said guides permitting the guides and carrier to adjust themselves to the work being done.

44. In a leather strap-finishing machine, coöoperating members forming grooves for receiving the edges of straps, the sides of said grooves being at an angle with each other and yielding means for pressing the coöoperating members toward each other, swinging brackets and rollers carried thereby, and cams operatively connected with said coöoperating members and with said brackets.

45. In a leather strap-finishing machine, edge finishing devices and means controlled by the thickness of straps for varying the lateral pressure of said finishing devices on the edges of straps, said means consisting of rollers to be engaged by passing straps, swinging brackets carrying said rollers, and cams operatively connected with said brackets and with said edge finishing device.

46. In a strap-finishing machine, means for operating on straps comprising a feeding device and cleaning devices, said cleaning devices comprising a rotating cone-shaped brush on each side of the path of the feeding device, said brushes and feeding device being constructed and arranged to feed a strap past said brushes with a face of said strap tangent to the work contacting surfaces of said brushes.

47. In a strap-finishing machine, means for operating on straps comprising a feeding device and cleaning devices, said cleaning device and cleaning devices,

ing devices comprising a rotating cone-shaped brush on each side of the path of the feeding device, said brushes having shafts arranged with an end of one shaft adjacent an end of the other shaft but spaced apart sufficiently to form a passage for the feeding device and said shafts being further arranged at an angle to each other such that the adjacent ends of the brushes contact with each other to close the passage of the feeding device.

48. In a strap-finishing machine, a feeding device for engaging and drawing straps through said machine, said feeding device having one or more teeth for insertion into

straps and one or more barbs on each tooth for preventing premature withdrawal of straps from said feeding device.

49. In a strap-finishing machine, a strap-finishing device for drawing straps through said machine, said device having a row of forwardly inclined teeth, the front tooth being inclined more than the rear tooth.

In testimony whereof, I set my hand in the presence of two witnesses, this 4th day of August, 1911.

FRANK K. RUSSELL,

Witnesses:

A. L. JACKSON,

ALBERT C. OLSON.
